UNITED STATES PATENT OFFICE.

THOMAS GRANT, OF NEW YORK, N. Y., ASSIGNOR OF ONE-HALF TO
HARTWIG A. COHEN, OF DALAMAR, NEVADA.

ICE-MACHINE..

SPECIFICATION forming part of Letters Patent No. 665,000, dated January 1, 1901.

Application filed July 25, 1899. Serial No. 725,039. (No model.)

To all whom it may concern:

Be it known that I, THOMAS GRANT, a citizen of the United States, and a resident of the borough of Richmond, New York city, in the county of Richmond and State of New York, have invented certain new and useful Improvements in Ice-Machines, of which the following is a specification.

The object of my invention is the production of an apparatus for refrigeration and ice-making, and in addition to its novel features is very simple in construction, eliminating parts heretofore used in apparatus of this type. Its operation depends upon the cooling effects obtained by the expansion of vapors and gases. With my apparatus air or other gas or vapor is first compressed, then cooled to its initial temperature before compression, and, lastly, allowed to expand while performing mechanical work, thereby lowering the temperature of the expanded air, gas, or vapor without generating heat due to frictional resistances.

My invention is particularly designed for the use of air, although any other gas or vapor or other refrigerant can be used, and to make the device efficient for ordinary air it is constructed to employ the air at high pressures to obtain the greatest cooling effects with small apparatus by the well-known principle that with the same number of expansions the cooling effect increases with the rise of the initial and terminal pressures of the air, gas, or vapor employed.

My device consists, essentially, of a single-cylinder compound compressor, a single-cylinder compound expander, a cooler, and suitable means to drive the machine, employing also the mechanical work performed in the expander during expansion to assist in propelling the apparatus.

To these ends my invention consists of the apparatus illustrated in the accompanying drawings, described in the specification, and pointed out in the claim herewith.

Figure 1 shows an elevation of my ice-machine. Fig. 2 represents a plan of the machine. Fig. 3 is a cross-section on line A' B' of Fig. 2. Fig. 4 shows an end elevation of the ice-machine. Fig. 5 is a fragmentary section and elevation of the cooler, the sec-

tion being taken on the line C' D' of Fig. 6. Fig. 6 shows a section of the cooler, taken on line E' F' of Fig. 5. Fig. 7 represents a vertical longitudinal section of the compressor, taken on line G' H' of Fig. 2. Fig. 8 is a vertical cross-section of the compressor, taken on line I' J' of Fig. 7. Fig. 9 shows a detail top view of the cross-head. Fig. 10 is an elevation of the cross-head. Fig. 11 is a section of expander on line K' L' of Fig. 12. Fig. 12 represents a horizontal section of the expander, taken on line M' N' of Fig. 3. Fig. 13 shows a horizontal section of expander-valve through its axis.

Referring to the drawings, my invention is shown to consist, essentially, of a single-cylinder compound compressor A, a single-cylinder compound expander B, a cooler C, a bed-plate D, pillow-blocks E and F, a scotch-yoke G, a cross-head H, a heart-shaped cam I, a roller J, a spindle L, with forked end l, a cross-bar M, a supporting-lever N, a fly-wheel or pulley O, connecting-pipes P, R, and S, and a crank-shaft T.

The compressor consists, essentially, of the water-jacketed cylinder A; the hollow transfer-piston A², with the transfer-valve a' held in place against the large diameter a¹² of the piston by the follower-ring a¹⁰, with bolts a¹¹; the inlet-valve a⁴, held in place by retaining-plate a⁵, the valve being secured by tightening the retaining-plate a⁵ against the back cylinder-head A³ by the nut a¹⁸; the cylinder-head A³, with inlet-opening a⁸ and reservoir a¹⁴, and the outlet-valve a⁷, with ring-cage a⁶, outlet-opening p, and flanged packing a⁹, the valve a⁷ and packing a⁹ being held in place by the cylinder-head A⁴ and internal flange of cylinder a¹⁵. The cylinder-head A⁴ is extended, as shown, to guide the piston A². A division-plate a¹⁶ is cast in the piston, which, with the pipes a¹⁷, allows a circulation of water therein.

The expander is shown to consist, essentially, of the cylinder B, cast with the valve-chest B³; the piston B², with cup-shaped packing b⁵ held in place by the follower-ring b¹⁷ and bolts b¹⁸; the valve B⁴, consisting of two portions b¹⁹ and b²⁰, secured on the valve-rod b¹², with an inlet-port at b⁶, an exhaust-port at b⁷, and a transfer-opening at b⁸, cup-shaped leather packings at b²¹, b²², and b²³; loose col-

lars b^{30} and b^{31} , nut b^{32} , and collar b^{33} , between the two latter of which the parts of the valve are adjustable; an exhaust-opening b^{10} , communicating with exhaust-cavity b^4 ; an inlet-opening at b^9 ; ports b^2 and b^3 , connecting cylinder B with valve-chest B³; bonnet B⁷, with extended throat to guide the piston, and flanged packing b^{24} , held in place between the bonnet B⁷ and cylinder-head B⁵.

10 The compressor A is shown bolted to the bed-plate D by the bolts a^8 , and the expander B is secured to the same bed-plate by the bolts b^{11} .

15 The pillow-blocks E and F are cast with the bed-plate.

20 The scotch-yoke G is keyed to the piston A² by the key x and bolted to the piston B² by means of the rod b^{13} and nuts b^{14} and b^{15} . It travels on the planed portion of the bed-plate D, between guides d' , which are bolted to the bed-plate by the bolts d^2 . The adjustable cross-head H operates in the scotch-yoke G.

25 To the crank-shaft T is keyed the heart-shaped cam I, which through the roller J, journaled in the forked end l of the spindle L, actuates through the cross-bar M the valve-rod b^{12} . The lever N is journaled to the bed-plate D by means of the spindle n , and its office is to support the spindle L. A spring 30 b^{16} actuates the spindle L, and consequently brings the roller J against the heart-shaped cam I.

35 The cooler C is bolted to the frame D by means of the bolts c through the flange c' , and, referring to Figs. 5 and 6, the cooler is shown to consist, essentially, of the heads C², pipe C³, and tubes c^4 . Bonnets c^5 are bolted to the heads. The opening c^6 leads to the inside of the tubes, and the opening c^7 connects 40 with the outside of the tubes to allow water circulation. A pipe P connects air-outlet opening p of the compressor with inlet-opening c^6 of the cooler, and pipe R connects outlet-opening c^7 of the cooler with inlet-opening b^9 of the expander.

45 In operating my machine it is used on a closed cycle and the air to be compressed enters the compressor at the inlet-opening a^3 , fills the reservoir a^{14} , and is drawn into the cylinder in the space contained between the retaining-plate a^5 and the enlarged head a^{12} of the piston by reason of the piston moving in the direction shown by the arrow, Fig. 7. When the piston moves in the opposite direction, the air contained in the space just referred to is transferred to the other side of the enlarged head a^{12} of the piston by the opening of the transfer-valve a' and in this process of being transferred is compressed, 50 because the volume of the air or gas is decreased by the entering of the smaller diameter A² of the piston into the cylinder. When the piston again moves in the direction shown by the arrow, Fig. 7, the air or vapor is subjected to further compression until the outlet-valve a^7 opens, and the contents are discharged through the outlet p into the pipe P.

It is thus evident that when the charge is transferred from one side of the enlarged head of the piston to the other a compression takes place and when the said charge is discharged from the cylinder it is again compressed, and receiving two compressions makes it a compound compressor. The air or gas then enters the inlet c^6 of the cooler C, where it is cooled by the water circulating on the outside of the tubes c^4 . The air leaves the cooler through the pipe R and enters the expander B through the opening b^9 , when it passes through the ports b^6 and b^3 into the cylinder 70 in the space between the cylinder-head B⁵ and the enlarged head of the piston, the space containing the smaller diameter B² of the piston, the piston traveling in the direction shown by the arrow, Fig. 12. When the piston has made a full or partial stroke, the valve B⁴ closes the port b^3 to the opening b^9 and causes the connection of the ports b^3 and b^2 by the transfer-opening b^8 , which causes the air or gas to escape from the side of the 80 piston toward the cylinder-head B⁵ to the side toward the cylinder-head B⁶, increasing the volume of the air or gas on account of the smaller diameter B² of the piston not being contained in the cylinder on this latter side. 85 The valve can be arranged to cut off the supply before the end of the stroke, which allows a certain expansion, and when the charge is transferred from one end of the cylinder to the other it evidently receives further expansion, and thus receiving two distinct expansions makes it a compound expander. When the piston is again moving in the direction shown, the air confined between the piston and the cylinder-head B⁶ escapes 90 by means of the port b^2 and exhaust-cavities b^7 and b^4 through the opening b^{10} , when it enters the refrigerating-coils of the system. A water-inlet pipe is attached to the cooler C at c^8 , the water leaving the cooler through 95 the piping S, which connects with the water-jacket of the compressor at s' and leaves through the opening shown at a^{20} .

Having described my invention, I claim and desire to secure by United States Letters Patent—

An ice-machine consisting of the combination; of a single-cylinder compound compressor, the plunger therein provided with an enlarged end and containing a cup-shaped valve; a cup-shaped inlet-valve, the turned-up edge of which is located near the cylindrical surface of the compressor; a retaining-plate securing the inlet-valve to the cylinder-head of said compressor; a cup-shaped outlet-valve, between a given cage and an internal flange upon said compressor; a single-cylinder compound expander, a plunger with enlarged head located therein; a piston-valve containing a valve-spindle, with two main 120 portions cored for the inlet and outlet ports of said expander, cup-shaped packing held on the spindle of said piston-valve between collars thereon and adapted to be easily ad-

justed; a cooler having two heads, with an outer shell and tubes; piping connecting the compressor and cooler, and piping connecting the cooler and expander, for the purpose of conducting the compressed air from compressor to cooler, and from cooler to expander; in combination with means for regulating the motions of the compressor and expander.

Signed at New York, in the county of New York and State of New York, this 11th day of 10 July, A. D. 1899.

THOMAS GRANT.
